FIG.1.

FIG.2.

FIG.3.

INVENTOR

Harry F. Hitner
by Atty.
James C. Bradley

UNITED STATES PATENT OFFICE.

HARRY F. HITNER, OF PITTSBURGH, PENNSYLVANIA.

SWITCH AND FUSE BOX.

Application filed December 9, 1920. Serial No. 429,456.

To all whom it may concern:

Be it known that I, HARRY F. HITNER, a citizen of the United States, and a resident of Pittsburgh, in the county of Allegheny and State of Pennsylvania, have made a new and useful Invention in Switch and Fuse Boxes, of which the following is a specification.

The invention relates to switch and fuse boxes, particularly those of the multiple type employing a plurality of fuse blocks with a corresponding switch for each block. It has for its principal objects the provision of a cheap, simple box construction, in which 10 (1) the switches may be operated without opening the box, (2) the fuse blocks and switches are very accessible for wiring and inspection; (3) the switches may be removed for inspection without disconnecting any 15 wiring connections; and (4) the wiring for any or all of the parts may be brought in from any side of the box and attached to the desired part without inconvenience. The invention is further designed to provide a 20 box having the above characteristics which may be made of sheet metal of light construction, presenting a good appearance with a narrow top to afford a minimum amount of dirt and water collecting surface. 25 One embodiment of the invention is illustrated in the accompanying drawings, wherein:—

Figure 1 is a perspective view of the improved box, Fig. 2 is a front view of the box 30 with the lid open and partially broken away, and Fig. 3 is a vertical section through the box. The box itself comprises the back wall 1, the end, top and bottom walls 2, 3 and 4, the front wall 5 and the lid 6. The top wall 40 3 is of less width than the bottom wall 4 which provides for the inclination of the cover 6 and gives a top wall of reduced area for the collection of dirt. The cover is hinged to the top wall by means of the 45 hinges 7—7, so that the cover may be swung up and out of the way.

The back wall preferably carries a series 50 of four fuse blocks 8, while the rear side of the front wall 5 is provided with a corresponding number of push switches 9. The push members of these switches extend through the front wall, so that the switches may be operated without opening the cover. The top and bottom and end walls are each 55 preferably provided with five openings or holes 10 for leading the wires into the box.

One of the five holes takes the main inlet and outlet wires, while each of the others takes the wires from one of the switches. The openings are provided on the four sides 60 so that the wires may be brought in on the side which is most convenient. One or more or all of the sets of wires may be brought in on any side of the box. The metal filling the holes is preferably not all punched out 65 and in installing the box the discs need be pushed out of those holes only which are to be used, so that there are no unnecessary openings leading into the box for the passage of moisture or dirt. 70

The fuse blocks and switches are spaced away from the side and top and bottom walls as indicated in Fig. 2, so as to provide a runway 11 for wires extending clear around the switches and plugs. This provides for the 75 convenient insertion of the wires from any side of the box and makes it relatively easy to distribute the wires in the box and attach and detach them.

Each switch is connected with its fuse 80 block and with the wiring leading to and from the box with sufficient slack or play so that when the screws 12 holding a switch in position are removed, the switch can be removed from the box for inspection without 85 detaching any of the wiring connections, which adds greatly to the convenience of inspecting.

The box is preferably made of sheet metal and the number of units in the box limited to 90 four circuits. It is not regarded as good practice to use more than this number of circuits without insulating lining and barriers. When it is desired to use a larger number of units, this is done by multiplying 95 the number of boxes as desired. From a standpoint of cost it is also more desirable to make the boxes all of the same size. When the door 6 is opened, as indicated in Fig. 2, all of the fuse blocks are exposed and 100 accessible for the replacement of fuses or for attention to the connections. Similarly with respect to the switches, each of which is readily accessible from above, although ordinarily the easiest method of attending to the 105 switches in connecting them up or inspecting them, is simply to remove the holding screws 12 and remove the switches from the box. The box affords a minimum amount of surface for the lodgment of dirt or moisture, is of pleasing appearance, and of relatively cheap construction. Other advantages 110

incident to the construction will be readily apparent to those skilled in the art.

What I claim is:

1. In combination in a switch and fuse box, a casing comprising a back wall, end and bottom walls, a front wall extending upward from the bottom wall a fraction only of the height of the back wall, a top wall of less width than the bottom wall, and a cover hinged to the top wall and inclined at an angle to the perpendicular when in closed position, a series of fuse blocks mounted on the upper portion of the back wall of the box opposite said cover, and a corresponding series of switches mounted on the front wall and operable from the outside of the box.
- 15 2. In combination in a switch and fuse

box, a casing comprising a back wall, a bottom wall, a front wall extending upwardly from the bottom wall only a fraction of the height of the back wall and leaving an opening at the upper portion of the box, side walls beveled back from the upper edge of the front wall to the top of the box, a cover for said opening, a series of fuse blocks mounted on the upper portion of the back wall of the box opposite said opening, and a series of switches mounted on the rear face of the front wall and operable from the outside of the box.

In testimony whereof, I have hereunto subscribed my name this 6th day of December, 1920.

HARRY F. HITNER.
